(57) **CLAIM**

The ornamental design for a diaper pail, as shown and described.

DESCRIPTION

FIG. 1 is a top, front, and right side perspective view of the diaper pail of the present invention.

FIG. 2 is a top plan view thereof.

FIG. 3 is a right side elevation view of thereof.

FIG. 4 is a left side elevation view of thereof.

FIG. 5 is a front elevation view thereof.

FIG. 6 is a rear elevation view thereof.

FIG. 7 is a top, rear, and left side perspective view thereof.

FIG. 8 is a top, front, and right side perspective view of the diaper pail of the present invention shown in use with a bin connected to the diaper pail, the bin being environment and forming no part of the claimed design; and,

FIG. 9 is a top, front, and right side perspective view of the diaper pail of the present invention shown in use with a wipes container connected to the diaper pail, the wipes container being environment and forming no part of the claimed design.

Elements drawn in dash-dot lines are included for illustrating portions of the diaper pail and form no part of the claimed design. Elements drawn in dash-dot-dot lines are included for illustrating the environment in which diaper pail is used and form no part of the claimed design.

1 Claim, 9 Drawing Sheets
